UNITED STATES PATENT OFFICE.

WILLIAM E. WOODARD, OF FOREST HILLS, NEW YORK.

CENTERING DEVICE FOR TRUCKS.

1,406,801.

Specification of Letters Patent. Patented Feb. 14, 1922.

Application filed April 23, 1920. Serial No. 375,967.

To all whom it may concern:

Be it known that I, WILLIAM E. WOODARD, a citizen of the United States, residing at Forest Hills, in the county of Queens and State of New York, have invented certain new and useful Improvements in Centering Devices for Trucks, of which the following is a specification.

My invention has reference to an improved device of the character specified which is intended for use primarily on locomotive engine trucks, but is also applicable to service on trucks for tenders or other railroad vehicles and the first of the objects of my present invention is to provide a centering mechanism for trucks of what are commonly called the swing or lateral motion type and which will afford such resistance to lateral motion as may be desired while permitting as large a degree of freedom in action as may be required by the deflection of the truck in passing curves or otherwise.

A further object of my present invention is the provision of improved means for stabilizing or centering the apparatus which permits the deflection; to provide for an increased wear capacity and at the same time permit of ready renewal of worn parts and replacement thereof with new ones with a minimum of trouble and expense.

In order that my invention may be better understood I will proceed to describe the same in connection with the accompanying drawings, wherein:

Figure 1 is an end elevation of a truck to which my invention is applied; Figure 2 is a plan view of such truck; Figure 3 is an enlarged figure showing in plan view the operative mechanism of my centering means; Figure 4 is a sectional view taken on the line 4-4 of Figure 3; Figure 5 is an enlarged detail of one of the pairs of centering devices; Figure 6 is an end elevation of the apparatus shown in Figure 5; and Figure 7 is a detailed view showing a method which I employ for conveniently and economically constructing one of the detailed parts.

Referring now more particularly to Figures 1 and 2 it will be seen that I have therein shown a truck such as is used commonly in locomotive practice in which there is a main frame 1 which is made in one piece of cast metal such as cast steel and which has

wheels 2, and an axle mounted in suitable

bearings in the manner common in apparatus of this class.

At the center of the truck is a center plate 3 which, as shown in Figure 4, is provided with a center pin 4 and a pair of downwardly extending flanges 5 that carry supporting plates 6 which rest upon the upper point or surface of the pairs of rocker members 7, the lower bearing surfaces of which at 8 are seated in grooves formed in the bearing strips 9 which are secured by bolts 10 on the upper side of the cross member or bridge 11, which latter in the construction shown is integral with the side members 12 of the unitary body of the truck.

Along the center line of the center plate transversely of the longitudinal axis of the truck, I provide on either side of the plate depending lugs 13 which are connected at each side with cooperating lugs 15 projecting upwardly from the center part of the rocking members, the connection between lugs 13 and 15 being by means of links 14 and pins 16.

By the arrangement just described both pairs of rocking members are held in proper position with relation to the other parts while at the same time permitting the downward extension of the center pin 4 which passes below the plate 11 so that it may be provided with a suitable pin or other securing device and as indicated in the drawing it will not be interfered with by the action of the links 14 or lugs 15.

As shown in Figures 5 and 6 I have made the rocker members with a middle part 17 having flanged ends 18 to which, by suitable rivets 19, there are secured the heart shaped members 20 which carry the load and are preferably made of harder material such as some form of special steel.

In Figure 7, I have shown a preferred method for forming the bearing strips 9 which are made of special durable steel of bar formation, two of which I place together as shown in this figure and while clamped in such position drill at the point marked 21 so that when the two bars are separated the two strips 9 on opposite sides of the center pin will have their recesses exactly aligned for proper support of the rocker members. By providing the bearing strips 9 between the plate 11 and the rocker members and arranging these strips so they may be readily replaced, I not only facili-

tate renewal or repairs where this is necessitated by wear of the rocker members upon the strips and also reduce the amount of wear by employing strips of harder material than the material of the main truck casting, but I am also enabled to do the necessary machining with very much less difficulty and expense than is required to machine the requisite seats at the bottom of 10 the pocket heretofore usually used.

It will be seen that in the arrangement above described, I have provided hard metal bearing plates or strips not only for the pocket of the truss frame, but also for the 15 face of the center plate which carries the bolster, and also for the surface or bearing faces of the rockers themselves and I have thus not only very substantially increased the durability of the several parts 20 which are subject to wear which, under heavy weights in the present construction is considerable, but I have also facilitated and cheapened the cost of construction of all of the said several parts and made it possible 25 to make replacement where necessary without loss or destruction either of the bolster, center pin casting or of any part of the main truck frame casting or of the body part of the rockers themselves.

30 It will be observed that while I have shown my invention as applied to a four wheel truck the same can be used in association with two wheel trucks or other types of construction.

35 I claim:

1. A double end centering device rocker for trucks having a body portion of relatively soft metal with attaching faces on its ends and centering devices of relatively 40 hard metal secured to the ends of said body portion.

2. A centering device for railway trucks having a center plate and center pin, rocker members on both sides of said center pin, 45 supporting seats for said rocker members and link connections between the center plate and each rocker member in vertical alinement on either side of the centering pin.

3. A self centering truck for railway vehicles comprising a truck frame having a 50 pocket for the centering parts provided with a bearing strip seat, a separate bearing strip seated in the pocket, a plurality of centering device seats in predetermined spaced relation formed in the bearing strip, centering rockers resting in said bearing strip seats in spaced relation, and means for securing said strip to the pocket.

4. A self centering truck for railway vehicles comprising a truck frame having a 55 substantially central pocket depending below

for receiving the centering parts, said pocket being provided with a bearing strip seat, a separate bearing strip seated in the pocket, centering rockers, a plurality of seats in predetermined spaced relation formed in the bearing strip and in which the rockers are journaled in spaced relation, and means for securing said strip to the pocket.

5. A self centering truck for railway vehicles comprising a truck frame having a bearing strip seat, a separate bearing strip seated thereon and provided with two pairs of spaced seats, a pair of rockers each journaled in one of said pairs of seats, and means 70 for securing said strip.

6. A self centering truck for railway vehicles comprising an integral truck frame having a pocket for the centering parts provided with a bearing strip seat, a separate bearing strip seated in said pocket, a plurality of centering device seats in predetermined spaced relation formed in the bearing strip, centering rockers resting in said bearing strip seats in spaced relation, and means 80 for securing said strips to the pocket.

7. A centering device for railway trucks having a center plate and a center pin, a rocker member on each side of said pin, and a link connection at each side of said pin between the rocker member and the center plate, said link connections lying in the vertical transverse plane which cuts the center of the pin.

8. A centering device for railway trucks 95 having a center plate and a center pin, a rocker member on each side of said pin, supporting seats for each of said rocker members at each side of the pin and placed at substantially equal distances from the pin longitudinally of the truck, and a link connection between the center plate and each rocker at each side of the pin, the point of attachment on the rocker members being substantially midway between the supporting seats.

9. A double end centering device rocker for trucks having a central body portion with centering members at each end and a lug connecting means on the body portion 100 midway between the centering members.

10. A self centering truck for railway vehicles comprising a truck frame having a bearing strip seat, a separate bearing strip seated thereon and provided with a plurality 115 of seats in predetermined spaced relation, rocking members journaled in said seats in spaced relation, and means for securing said strip.

In testimony whereof, I have hereunto 120 signed my name.

WILLIAM E. WOODARD.
